GARMENT HANGER

Lloyd W. Walker, Harvey, Ill., assignor to Lloyd W. Walker, William H. Walker, Kathleen D. Walker, and Rose E. Walker, copartners, doing business as Walker Metal Products Company, Harvey, Ill.

Application May 27, 1949, Serial No. 95,699

14 Claims. (Cl. 223—91)

1

The invention relates generally to garment hangers and, more particularly, to hangers of the character that employ a pair of clamping bars between which the garment is positioned.

The present invention has among its objects the production of a garment hanger which may be employed for supporting two or more garments, as for example, a coat and a pair of trousers or a skirt, which hanger is very simple in construction, inexpensive to manufacture, and efficient for the purpose intended.

Another object of the invention is the production of such a hanger in which provision is made for urging the clamping members apart, at the same time providing means for supporting the second garment, such as a coat or the like.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters indicate like or corresponding parts:

Fig. 1 is a front elevational view of the hanger embodying the present invention with the hanger illustrated in closed position;

Fig. 2 is a top plan view of the hanger illustrated in Fig. 1 with the hanger in open position;

Fig. 3 is a sectional view taken approximately on the line 3—3 of Fig. 2; and

Fig. 4 is a sectional view taken approximately on the line 4—4 of Fig. 1.

Referring to the drawings, and particularly to Figs. 1 and 2, the reference characters 1, 1 designate a pair of clamping members or bars adapted to receive and clamp a garment between the same for supporting a garment such as a pair of trousers, a skirt, or the like, the member 1 being constructed of suitable material, as for example, wood, or the like. The members are supported in operative relation by a pair of members 2 and 3, respectively, illustrated in the present instance as being formed from substantially rigid rods, each bent into a generally U-shape, the rod 2 having an intermediate portion 4 and leg portions 5, and the rod 3 having an intermediate portion 6 and leg portions 7. The free ends of the legs 5 and 7 of the respective members are connected to the respective clamping members 1, the latter, in the present instance having bores 8 of a size to receive the respective

ends, forming a press fit therebetween whereby the members 1 are rigidly connected to the respective members 2 and 3. The intermediate portion 6 of the member 3 is provided with a pair of coils 9 aligned with and encircling the horizontal portions 11 of the intermediate portion 4 of the member 5 to form a hinged connection between the two supporting members. Thus the members 1 may be rotated into clamping position, as illustrated in Figs. 1 and 4, or separated, as illustrated in Figs. 2 and 3.

As illustrated in Figs. 1 and 2, the intermediate portion 4 of the member 2 is provided with a downwardly offset horizontal portion 12 connected to the portions 11 by substantially parallel legs 13, and in like manner the intermediate portion 6 of the member 3 is provided with a downwardly offset horizontally extending portion 14 connected to coils 9 by the legs 15. Pivoted 10 mounted on the horizontal portion 14 of the member 3 is an L-shaped lever 16 flattened at one end and curled around the portion 14 of the member 3 to form an eye 17, as illustrated in Figs. 3 and 4. The end of the lever 16 adjacent 15 the eye 17 is bent to form a transversely extending portion 18, the opposite or free end of the lever being bent to form a hook 19, by means of which the device may be suspended from a rod, or other support, the hook 19 lying in a plane 20 approximately parallel with the clamping members 1 when the latter are in a closed position. The portion 18 of the lever 16 is positioned below the horizontal portion 12 of the rod 2, and is so proportioned that rotation of the lever 16 in 25 an upward direction will cam the portion 12 toward the portion 14, thereby drawing the clamping members 1 together, as illustrated in Fig. 4. To facilitate this action, the portion 12, if desired, may be provided with a small collar or sleeve 21 of a softer metal than the rods forming the lever 16, whereby less friction will be produced between the lever and the portion 12 during the closing operations than would be the case if the frictional engagement were between two like 30 materials. The sleeve 21 may be clamped, or otherwise rigidly secured, to the portion 12.

Carried, in the present instance, by the member 1 connected to the rod 3 is an elongated rod, indicated generally by the numeral 22, bent to form a pair of more or less aligned elongated loops 23, connected to one another through an intermediate portion 24, the free ends 25 of the member 22 extending downwardly, as indicated at 26, and inserted in bores 27 in the adjacent member 1, the ends 25 being held in engagement

with the member 1 by a press fit, or the like. As illustrated in Fig. 1, the loop portions 23 of the member 22 are inclined downwardly, whereby the loops may be employed as a hanger for supporting a coat or other garment. The member 22 is formed from a more or less resilient material, with the loops 23 being so shaped that the intermediate connecting portion 24 of the member tends to assume a position such as illustrated in Figs. 2 and 3, with such intermediate portion 24 spaced from the juncture of the upwardly extending portions or legs 25, with the adjacent ends of the loops 23, whereby the intermediate portion 24 will engage the legs 5 of the rod 2, tending to rotate the latter and the member 1 associated therewith outwardly away from the other member 1, as illustrated in Figs. 2 and 3. The member 22 thus exerts a spring action between the rods 2 and 3, and supporting members 1, urging the same apart about their hinged connection. Referring to Fig. 4, it will be noted that the intermediate connecting portion 24 of the member 22 is positioned above the portion 18 of the lever 16 when the device is in closed position, so that the downward movement of the member 22 under the load of a heavy garment, or the like, carried upon the loop portions 23, is restricted by the portion 18, so that all the downward load on the intermediate portion 24 is directly transmitted to the hook 19. Thus only part of the weight of the garment hanging on the member 22 is carried through the legs 25 and member 1, the bulk of the weight of the garment being transmitted directly to the hook. Downward force on the member 1 carrying the member 22, which force would be in a direction tending to separate the member 1 from rod 3, is thus reduced to a safe minimum.

It will be noted that the construction herein described provides a very simple hanger adapted to support a coat or other garment, as well as a pair of trousers or skirt, and provided with a spring action tending to separate the clamping members when the device is opened. Likewise, it will be apparent that as the single member 22 provides both the spring action and additional garment supporting structure, eliminating the use of coiled or other wire springs, etc., the device may be manufactured and retailed for approximately the same amount as the usual clamping type of trouser hanger having no provision for supporting a coat, or the like; and as the member 22 is constructed of relatively stiff material, with the spring action being produced by the relatively long looped portions, a very smooth positive spring action is achieved, although the closing force required is approximately the same as that in other spring actuated hangers of the clamping type.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a garment hanger, a pair of clamping members, a bent wire rod for each of said members having both ends secured to the corresponding member, with an intermediate portion of one rod coiled about an intermediate portion of the other rod to form a hinge; a clamping lever piv-

oted to one of said rods and engageable upon rotation thereof with the other rod to draw said clamping members together, the free end of said lever being hook-shaped to provide means by which the hanger may be supported, and a bent wire rod having its ends secured to one of said clamping members, said last-mentioned rod extending outwardly beyond the ends of the respective clamping members and looped back to form an intermediate portion extending between the two first-mentioned rods and engageable with the rod carrying the other clamping member to exert a force thereon tending to separate the two clamping members.

2. In a garment hanger, a pair of clamping members, a bent wire rod for each of said members having both ends secured to the corresponding member, with an intermediate portion of one rod coiled about an intermediate portion of the other rod to form a hinge, a clamping lever pivoted to one of said rods and engageable upon rotation thereof with the other rod to draw said clamping members together, the free end of said lever being hook-shaped to provide means by which the hanger may be supported, and a bent wire rod having its ends secured to one of said clamping members, said last-mentioned rod extending outwardly beyond the ends of the respective clamping members and looped back to form an intermediate portion extending between the two first-mentioned rods and overlying a portion of said clamping lever, whereby downward movement of the last-mentioned intermediate portion is limited, and downward stresses thereon may be transmitted directly to the clamping lever and the hook formed thereon.

3. In a garment hanger, a pair of hinged members having oppositely disposed portions adapted to clamp a garment therebetween, a movable lever carried by one of said hinged members and engageable with the other hinged member for drawing said clamping portions into clamping position, said lever being provided with means engageable with a support from which the device may be suspended, and a garment supporting member connected to one of said hinged members having a pair of oppositely extending garment supporting portions, each extending outwardly beyond the adjacent ends of the clamping portions of the hinged members, and having an intermediate portion overlying a portion of said lever, whereby downward stresses on said garment supporting member may be transmitted through said intermediate portion to the adjacent portion of said lever.

4. In a garment hanger, a pair of hinged members having oppositely disposed portions adapted to clamp a garment therebetween, a resilient member having a pair of oppositely extending portions, each extending outwardly beyond the adjacent ends of the clamping portions of the hinged members, said resilient member having portions thereof engaged with the respective hinged members and exerting a force thereon tending to separate said clamping portions, and means for drawing said clamping portions into clamping position in opposition to said separating force.

5. In a garment hanger, a pair of hinged members having oppositely disposed portions adapted to clamp a garment therebetween, a resilient wire rod secured to one of said hinged members extending outwardly beyond the ends of the respective clamping portions, and looped back to form an intermediate portion extending between

the hinged members and engageable with the other of said hinged members to exert a force thereon tending to separate said clamping portions, and means for drawing said clamping portions into clamping position in opposition to said separating force.

6. In a garment hanger, a pair of hinged members having oppositely disposed portions adapted to clamp a garment therebetween, a wire rod secured to one of said hinged members extending outwardly beyond the ends of the respective clamping portions and looped back to form a pair of loops connected by an intermediate portion, the latter being engageable with the other of said hinged members to exert a force thereon tending to separate said members, and means for drawing said clamping portions into clamping position in opposition to said separating force.

7. In a garment hanger, a pair of hinged members having oppositely disposed portions adapted to clamp a garment therebetween, a pair of generally U-shaped, resilient wire loops, each extending outwardly beyond a respective pair of corresponding ends of said oppositely disposed clamping portions, with the ends of the loops being positioned adjacent said hinged members, one end of each loop being secured to one of the hinged members, the other ends of the loops being operatively related to the other of said hinged members, whereby said loops exert a force on said members tending to produce relative movement therebetween, and means related to both of said members for relatively moving the same in opposition to such force.

8. In a garment hanger, a pair of members each comprising an elongated clamping element and a wire rod of generally U-shape, the free ends of each rod being secured to its associated clamping element, the intermediate portions of said rods being engaged to form a hinge about the axis of which said clamping members are relatively movable toward or away from each other, a pair of resilient, generally U-shaped wire loops, each extending outwardly beyond a respective pair of corresponding ends of said clamping elements, with the corresponding ends of said loops being positioned adjacent said U-shaped rods, one corresponding end of each loop being bent transversely thereto and secured to the clamping element of one of said members, the other corresponding ends of the loops being operatively related to the other member, whereby said loops exert a force on said members tending to produce separating movement between said clamping elements, and means related to both of said U-shaped rods for producing relative movement of said clamping elements toward each other in opposition to such force.

9. In a garment hanger, a garment supporting member constructed from a wire rod bent to form a pair of oppositely extending, generally U-shaped loops, the legs of which are adjacent one another, a corresponding leg of each loop being connected by an intermediate portion integrally formed with such legs, the free ends of the other corresponding legs each terminating in a portion extending transversely to the remainder of the respective leg, with said transverse portions extending in the same general direction in opposed relation, a connecting member to which said transverse end portions of the legs are secured, and a hook structure secured to said connecting member from which the lat-

ter and said garment supporting member may be supported.

10. In a garment hanger, a garment supporting member constructed from a wire rod bent to form a pair of oppositely extending, generally U-shaped loops, the legs of which are adjacent one another, a corresponding leg of each loop being connected by an intermediate portion integrally formed with such legs, the free ends of the other corresponding legs each terminating in a portion extending transversely to the remainder of the respective leg, with said transverse portions extending in the same general direction in opposed relation, a connecting member to which said transverse end portions of the legs are secured, and a hook structure secured to said connecting member from which the latter and said garment supporting member may be supported, said hook structure having a laterally extending portion underlying the intermediate portion of said garment supporting member, whereby downward stresses on said garment supporting member may be transmitted through the intermediate portion thereof to said hook structure.

11. In a garment hanger, a garment supporting member constructed from a wire rod bent to form a pair of oppositely extending, generally U-shaped loops, the legs of which are adjacent one another, a corresponding leg of each loop being connected by an intermediate portion integrally formed with such legs, the free ends of the other corresponding legs each terminating in a portion extending transversely to the remainder of the respective leg, with said transverse portions extending in the same general direction in opposed relation, a connecting member to which said transverse end portions of the legs are secured, a hook member, means for securing said hook member to said connecting member, whereby the latter and said garment supporting member may be supported therefrom, said hook member having a laterally extending portion underlying the intermediate portion of said garment supporting member, whereby downward movement of said intermediate portion is limited and downward stresses thereon may be transmitted directly to said hook member.

12. The combination in a garment hanger including a garment support having a pair of hinged members having oppositely disposed portions adapted to clamp a garment therebetween, and means for drawing said portions together into clamping position including a hook structure adapted to support the garment hanger, of another garment support comprising a wire rod bent to form a pair of oppositely extending, generally U-shaped loops, the legs of which are contiguous to one another, a corresponding leg of each loop being connected by an intermediate portion integrally formed with such legs and extending transversely to said hinged members, the free ends of the other corresponding legs each terminating in a portion extending transversely to the remainder of the respective legs, with said transverse portions extending in the same general direction in opposed relation, said last mentioned transverse portions affixed to one of said oppositely disposed portions, and said hook structure operatively connected to one of the aforesaid oppositely disposed portions, whereby the oppositely disposed portions of the first mentioned garment support and the second mentioned garment support may be supported.

13. In a garment hanger, a pair of hinged mem-

7
bers having oppositely disposed clamping portions adapted to clamp a garment therebetween, a resilient wire rod having the ends thereof formed transverse to the oppositely disposed clamping portions and secured to one of the disposed clamping portions of said hinged members and also including an intermediate portion extending laterally of the hinged members and deformed to engage the other of said hinged members to exert a force thereon to separate said clamping portions, and means for drawing said clamping portions into clamping position in opposition to said separating force.

14. A garment hanger comprising one garment hanger including a pair of hinged members having oppositely disposed clamping portions adapted to clamp a garment therebetween, another garment hanger including oppositely extending resilient loop portions secured to one of said

10
hinged members and extending outwardly beyond the ends of the respective clamping portions, said loop portions operatively connected to the other of said hinged members and exerting a force thereon tending to separate said clamping portions, and means for drawing said clamping portions into clamping position in opposition to said separating force.
